UNITED STATES PATENT OFFICE.

FREDERIC E. BAGER, OF KENOSHA, WISCONSIN, ASSIGNOR TO FREDERICK C. AUSTIN, OF CHICAGO, ILLINOIS.

LIQUID-DISTRIBUTOR DISCHARGE MECHANISM.

1,421,373.

Specification of Letters Patent. Patented July 4, 1922.

Application filed February 17, 1917. Serial No. 149,211.

To all whom it may concern:

Be it known that I, FREDERIC E. BAGER, a citizen of the United States of America, and resident of Kenosha, Kenosha County, 5 Wisconsin, have invented a certain new and useful Improvement in Liquid-Distributor Discharge Mechanism, of which the following is a specification.

My invention relates to means for distributing oil on roads.

Generally stated, the object of my invention is to provide a novel and improved form of nozzle or discharge mechanism which can be easily controlled, and which 15 will properly distribute the oil on the roads.

A special object is to provide an improved construction and arrangement which will obviate the necessity of employing shut-off valves in the pipes leading to the nozzles, in 20 order to control the discharge of the oil from the nozzles, and which will, at the same time, provide means for regulating the discharge in the desired manner.

It is also an object to provide certain details and features of construction and combinations tending to increase the general efficiency and reliability of a mechanism for discharging oil or other liquid, of this particular character.

To these and other useful ends, my invention consists in matters hereinafter set forth and claimed.

In the accompanying drawings:

Fig. 1 is a rear elevation of an oil-distributing machine having a discharge mechanism embodying the principles of my invention, the upper portion of the oil tank or reservoir being broken away for convenience of illustration.

Fig. 2 is a plan view of the discharge mechanism shown in Fig. 1.

Fig. 3 is a side elevation of said mechanism, and of the pump therefor.

Fig. 4 is an enlarged front elevation of a 45 portion of one of the discharge-nozzles, partly in section, and showing means for guarding the discharge.

Fig. 5 is a vertical section on line 5—5 in Fig. 4.

Fig. 6 is a perspective of a portion of one 50 of the swinging deflectors, showing the means for governing the discharge.

As thus illustrated, my invention comprises a pair of horizontally disposed and transversely arranged nozzle-tubes A connected by pipes a and a pump B with the rear end of the tank C, which latter is suitably supported on an automobile truck of which D—D are the rear wheels. The nozzle-pipes A are provided on their under sides, a little to the rear, with discharge-openings 1, so that when the pump is operating the oil is drawn from the tank and discharged on the street. The deflector-plates E are disposed in rear of the nozzles A, being pivoted at e to swing about a horizontal and transversely disposed axis. Hand-levers F can be provided and secured to said deflectors to operate them about said axis. Each deflector is provided with a plurality of valve-plugs 2 which are disposed in position to enter the openings 1, and which are provided with beveled ends 3 to gradually close said openings when the deflectors are swung forward against the nozzles. Washers 4, of suitable material, such as rubber or leather, are provided at the base of the plugs 2 (see Fig. 5), thereby to tightly close said openings 1 when the deflectors are swung forward. The bevel 3 of each valve-plug is 80 preferably grooved longitudinally thereof, and when the openings 1 are entirely opened the jets of oil discharging therefrom will impinge upon the deflectors E at points immediately below the blocks 5 thereon, 85 which latter support the valve-plugs, and between the upwardly converging blocks 6, which latter are mounted on the deflectors to direct the discharge downward against the road or street surface. With this construction, each jet of oil will be converted into a fan-shaped spray, and the discharge can be regulated by adjusting the deflectors E either toward or away from the nozzles.

With this construction no shut-off valves 95 are necessary in the pipes between the nozzles and the tank. When the discharge is shut off, there will be no dripping of the oil from the nozzles, for the reason that the discharge is controlled at the nozzle-openings, 100 and there is no quantity of oil left in the nozzles which is free to discharge after the supply is shut off, as would be the case if the discharge were governed by valves be-

tween nozzles in the tank. In addition, the valve-plugs 3 prevent the openings 1 from clogging.

I do not, of course, limit myself to any particular use for my invention, nor to the exact construction shown and described, as it is obvious that a valve-mechanism or discharge-mechanism involving the principles of my invention can be used for various purposes and in various forms without departing from the spirit of my invention.

With the foregoing construction it will be seen that the jet of water issues from an opening and will always impinge substantially upon the same point or spot on the deflector E, regardless of whether the opening is entirely opened or only half opened, so that the varying of the discharge does not materially change the character of the discharge of the liquid onto the street. The cylindric valve-member 2 fits the opening 1, when the valve is entirely closed, but the curved upper surface of the valve-member 2 always bears against the upper edge of the discharge opening.

What I claim as my invention is:—

1. A liquid - distributor-discharge-mechanism comprising outlet-means to form a jet, a movable deflector disposed in position to receive the discharge from said outlet-means and formed to direct the liquid downward in a flat fan-shaped spray, and valve-means mounted on said deflector and arranged to cooperate with said outlet-means to so control the discharge that the size of the jet may be varied without materially changing its point of impingement on said deflector.

2. A liquid - distributor-discharge-mechanism comprising outlet-means, a movable deflector disposed in position to receive the discharge from said outlet-means and formed to direct the liquid downward in a flat fan-shaped spray, and valve-means mounted on said deflector and arranged to cooperate with said outlet-means to so control the discharge that the size of the jet may be varied without materially changing its point of impingement on said deflector, said deflector being pivoted to swing about a horizontal axis extending transversely of the direction of travel, said outlet-means consisting of a series of discharge-openings, said valve-means consisting of portions arranged to enter said discharge-openings and shaped to produce a variable discharge by adjustment of the deflector about its axis, and said deflector having means to limit spreading of the discharge.

3. A liquid - distributor-discharge-mechanism comprising outlet-means, a movable deflector disposed in position to receive the discharge from said outlet-means and formed to direct the liquid downward in a flat fan-shaped spray, and valve-means mounted on said deflector and arranged to cooperate

with said outlet-means to so control the discharge that the size of the jet may be varied without materially changing its point of impingement on said deflector, said outlet-means consisting of a series of discharge openings, and said deflector having means to limit spreading of the discharge.

4. A liquid - distributor-discharge-mechanism comprising outlet-means, a movable deflector disposed in position to receive the discharge from said outlet-means and formed to direct the liquid downward in a flat fan-shaped spray, and valve-means mounted on said deflector and arranged to cooperate with said outlet-means to so control the discharge that the size of the jet may be varied without materially changing its point of impingement on said deflector, said valve-means comprising a plug having a beveled end-portion to produce said variable discharge when moved into and out of said outlet-means by the adjustment of the deflector.

5. A liquid - distributor-discharge-mechanism comprising outlet-means, a movable deflector disposed in position to receive the discharge from said outlet-means and formed to direct the liquid downward in a flat fan-shaped spray, and valve-means mounted on said deflector and arranged to cooperate with said outlet-means to so control the discharge that the size of the jet may be varied without materially changing its point of impingement on said deflector, said deflector consisting of a swinging plate disposed behind said outlet-means, so that said deflector and outlet-means extend parallel with each other and transversely of the direction of travel, with the lower edge of said deflector a distance above the street surface, and means for rocking said deflector.

6. A liquid - distributor-discharge-mechanism comprising outlet-means, a movable deflector disposed in position to receive the discharge from said outlet-means and formed to direct the liquid downward in a flat fan-shaped spray, and valve-means mounted on said deflector and arranged to cooperate with said outlet-means to so control the discharge that the size of the jet may be varied without materially changing its point of impingement on said deflector, said deflector being mounted to swing about a horizontal axis, and said valve-means being curved about said axis.

7. A liquid - distributor-discharge-mechanism comprising outlet-means having a round opening to form a jet, and valve-means arranged to cooperate with said outlet-means to control the discharge, said valve-means including a movable valve-member which is cylindric in form and tapered at its end to variably restrict the round discharge opening at the upper side only, thereby to vary the dimension or size of the

- jet by movement of said member relative to said outlet-means, in combination with a flat plate to the face of which said valve member is fixed and which deflects the liquid 5 downward in a flat fan-shaped spray.
8. A liquid - distributor-discharge-mechanism comprising outlet - means having a round opening to form a jet, and valve-means arranged to cooperate with said outlet-means to control the discharge, said 10 valve - means including a movable valve-member tapered to variably restrict the discharge opening at the upper side only, thereby to vary the dimension or size of the jet 15 by movement of said member relative to said outlet-means, said member being beveled on the lower side only and means at the base of said valve-member to tightly close said opening, in combination with a flat 20 plate to the face of which said valve-member is fixed and which deflects the liquid downward in a flat fan-shaped spray.
9. In a street spraying machine, the combination of a transversely arranged pipe 25 provided at one side thereof with a row of discharge openings, a flat plate disposed opposite said openings, said plate extending beyond the ends of said row, means on said pipe to form a hinge for the upper edge of 30 the plate, so that the plate can be swung toward and away from said openings, means to operate said plate, and means on the face of said plate to control said openings, adapted to close the openings when the plate 35 is swung toward the pipe, and adapted to gradually open said openings when the plate is swung away from the pipe, said plate
- forming a deflector to receive the discharge from said openings, and serving to convert the discharge from the different openings 40 into a flat spray which is directed downward upon the street.
10. A structure as specified in claim 9, said plate having upwardly converging deflectors at opposite sides of each point on 45 the plate where the discharge impinges thereon.
11. A valve mechanism comprising a hollow member provided with a discharge opening, a swinging support disposed opposite 50 said opening, a valve member carried on said support and adapted to enter said opening, said member having its upper side and a portion of its lower side curved about the axis of said support, the other portion of 55 the lower side of said member being formed with a flat bevel, so that said member tapers toward its end when viewed from the side, thereby in effect to vary the size of said discharge opening when said support is moved 60 toward or away from said hollow body, and means at the base of said valve member to tightly close said opening.
12. A structure as specified in claim 11, said support having a flat deflecting surface 65 immediately below said valve member, which surface receives the discharge from said opening, thereby to deflect the discharge downward in the form of a fan-shaped spray. 70

Signed by me at Chicago, Illinois, this 31st day of January, 1917.

FREDERIC E. BAGER.
